PROCESS FOR REFINING SOUR HYDROCARBON OIL

Lawrence M. Henderson, Narberth, Pa., assignor to The Atlantic Refining Company, Philadelphia, Pa., a corporation of Pennsylvania

No Drawing. Application January 9, 1931
Serial No. 507,765

4 Claims. (Cl. 196—33)

The present invention relates to the art of refining hydrocarbon oils, and has particular reference to an improvement in that type of process for treating hydrocarbon oils, such as petroleum and its products, commonly known as the "doctor treatment", whereby the sulfur content thereof is effected.

The doctor treatment comprises washing a "sour" oil, that is, an oil which contains mercaptans, with a doctor solution which comprises an alkaline solution of lead oxide or litharge, whereby lead mercaptides are formed by reaction of the doctor solution with mercaptans contained in the oil. Although lead mercaptides of low molecular weight, for example, ethyl mercaptide, are insoluble in oil and precipitate upon formation, the lead mercaptides of higher molecular weight are oil soluble and therefore remain in solution in the oil after the doctor solution is separated from the oil. For this reason, it is customary in the art to add elementary sulfur to the oil, thereby forming organic disulfides and insoluble lead sulfide by reaction of the sulfur with the lead mercaptides. In practice the elementary sulfur is customarily added to the oil prior to or simultaneously with the addition of the doctor solution, although it is possible to withhold addition of the sulfur until the spent doctor solution has been separated from the oil.

The addition of elementary sulfur to litharged oil for the purpose of "breaking" the oil, that is, for precipitating lead sulfide is objectionable in that an unavoidable excess of sulfur is customarily employed. This excess sulfur remains in solution in the oil, thereby increasing the total sulfur content thereof, and causing the oil to react to the corrosion test.

A primary object of the present invention is to provide a process for breaking litharged oils so that the objections incident to breaking such an oil with elementary sulfur are avoided.

I have found that litharged oil may be broken, with the consequent formation of an insoluble lead-containing precipitate, by treating the litharged oil after separation of the doctor solution therefrom with an aqueous solution of cupric chloride.

In accordance with my invention a sour oil, for instance, a sour gasoline or lamp oil, is treated with a solution of sodium plumbite or doctor solution in any well known manner. For example, the doctor solution may be added to the oil and the mixture agitated to insure proper contact. After proper reaction the mixture may be settled

er layer may be separated by draining. As cupric chloride is an acid salt it is preferred to wash the litharged oil with water subsequent to the separation of the spent doctor solution. Otherwise small amounts of cupric chloride will be lost to the residual alkali of the litharged oil. The water wash, however, does not remove from the oil the lead mercaptides which were formed by treatment with the doctor solution.

To the litharged oil is then added an aqueous solution of cupric chloride, and the resultant mixture is thoroughly agitated to provide proper contact between the cupric chloride and the lead mercaptides contained in the oil. There results the formation of a white precipitate which is found to contain lead chloride. Upon completion of the reaction the mixture is allowed to stand, with the formation of a two-layer system. The lower layer of this system comprises the spent cupric chloride solution in admixture with the precipitate of lead chloride, while the upper layer consists of the oil which is now sweet and free from lead and copper compounds. These layers may be separated, for example, by decanting the oil.

It is preferred that the cupric chloride solution contain at least 10% cupric chloride at the beginning of a run, and it is possible to employ a saturated solution of cupric chloride to advantage. Ordinarily, a cupric chloride solution of about 20% concentration is preferred.

The amount of cupric chloride solution necessary to completely break the oil and render it sweet will depend upon such factors as the amount of lead mercaptides present in the oil and the concentration of the cupric chloride solution. It is to be pointed out that an advantage of my process over the customary procedure of breaking litharged oils with elementary sulfur is that the addition of an excess of my cupric chloride solution over the amount necessary to break the oil is harmless, and in fact expedites the reaction.

A further advantage of my process is that it may be carried out semi-continuously or continuously, in a manner which one skilled in the art will immediately recognize.

My invention will be further understood by reference to the following example of its operation.

A quantity of gasoline obtained by thermal decomposition of a gas oil from a West Texas crude oil was washed with a caustic solution to remove hydrogen sulfide, and then treated with an aqueous solution of sodium plumbite. After separation of the plumbite solution the gasoline was water washed. To 250 parts by volume of this gasoline was added 25 parts by volume of a 20% gasoline

aqueous solution of cupric chloride, and the mixture was agitated to insure proper contact. A white precipitate formed, and upon allowing to insure proper contact. A white precipitate formed, and upon allowing the mixture to stand, this precipitate settled out along with the cupric chloride solution to form a lower layer. After separation from this lower layer the gasoline was found to be sweet to the doctor test and free from lead compounds. The same cupric chloride solution was used to break 10 additional batches of the litharged oil, each batch comprising 250 parts by volume of oil. Thereafter the copper chloride solution failed to break further quantities of the litharged oil, indicating that the solution was exhausted.

Whereas, the above description is specific to cupric chloride, other cupric compounds coming within the scope of my invention, namely other 20 cupric halides or salt mixtures, such as a mixture of cupric sulfate and sodium chloride, which on being put into solution ionize to provide copper and halide ions, are intended to be covered in the appended claims as equivalents, and the term 25 "cupric chloride" as used in said claims is to be understood to include such equivalents.

What I claim is:—

1. A process for refining a sour hydrocarbon oil, which comprises treating said oil with a solution 30 of sodium plumbite, whereby oil soluble lead compounds are formed separating the oil from said treating solution, treating the separated oil with an aqueous solution of cupric chloride, thereby to form lead compounds which are insoluble in oil, 35 and separating the oil from said aqueous solution

and from insoluble substances resulting from the treatment with said aqueous solution.

2. In the process of refining a sour hydrocarbon oil, which comprises treating said oil with a solution of sodium plumbite, whereby oil soluble lead compounds are formed, and separating said treating solution from the oil, the step of precipitating insoluble compounds of lead from said oil by treatment with an aqueous solution of cupric chloride.

3. A process for refining a sour hydrocarbon oil, which comprises treating said oil with a solution of sodium plumbite, whereby oil soluble lead compounds are formed separating the oil from said treating solution, treating the separated oil with an aqueous solution of copper chloride containing at least substantially 10% cupric chloride, thereby to form lead compounds which are insoluble in oil, and separating the oil from said aqueous solution and from insoluble substances resulting from the treatment with said aqueous solution.

4. A process for refining a sour hydrocarbon oil, which comprises treating said oil with a solution of sodium plumbite, whereby oil soluble lead compounds are formed separating the oil from said 100 treating solution, washing the separated oil with water, treating the washed oil with an aqueous solution containing at least substantially 10% cupric chloride, thereby to form lead compounds which are insoluble in oil, and separating the oil 105 from said aqueous solution and from insoluble substances resulting from the treatment with said aqueous solution.
